UNITED STATES PATENT OFFICE.

FREDERICK A. SCHNEIDER, OF WASHINGTON, DISTRICT OF COLUMBIA, ASSIGNOR TO
HELEN B. SCHNEIDER, OF WASHINGTON, DISTRICT OF COLUMBIA.

PENCIL-CLASP.

No. 865,981.

Specification of Letters Patent.

Patented Sept. 10, 1907.

Application filed December 19, 1906. Serial No. 348,561.

To all whom it may concern:

Be it known that I, FREDERICK A. SCHNEIDER, a citizen of the United States, residing at Washington, in the District of Columbia, have invented a certain new 5 and useful Improvement in Pencil-Clasps, of which the following is a full, clear, and exact description.

This invention is designed to provide an efficient clasp for holding a pencil or like smooth surface article in a pocket against liability of escape from the pocket.

10 The invention consists of a socket-piece, which may or may not be elastic, to receive the pencil, and a spring serving the double purpose of retaining the pencil in the socket-piece and grasping the edge of the pocket to prevent loss of the pencil, the construction of the spring 15 being such, substantially as hereinafter particularly described and claimed, that its pencil-engaging element operates independently of the pocket-engagement element and is always in direct engagement with the pencil both when the device is in the pocket and 20 out of the pocket.

In the accompanying drawings, illustrating the invention, in the several figures of which like parts are similarly designated, Figure 1 is a perspective view. Fig. 2 is a side elevation showing the pencil in place in 25 dotted lines. Fig. 3 is a front elevation showing the pencil in place in dotted lines. Fig. 4 is a top plan view.

The whole device may be made of wire with a socket-piece 1 formed of several coils, which may be, though 30 not of necessity, elastic, or the socket-piece may be of other material, and in any case it is adapted to freely receive a pencil or other like article to be carried in the pocket.

Projecting from the socket-piece and rigid with it is a 35 limb 2 bent back upon itself and having the free limb 3, which terminates in a bar 4 extending transversely across the socket-piece. The part composed of members 2 and 3 is bent so as to constitute a hook to be hooked on to the edge of a pocket. The limb 3 is a 40 spring lever and its bar 4 a sort of fulcrum bearing

against the pencil and thereby transmitting the force of the spring to the pencil to hold it in forcible engagement with the socket-piece. By bending the limb 2 more or less tension may be imparted to the limb 3. It is intended that the bar 4 shall be normally forced over 45 the socket-piece by the resilience or tension of the spring limbs, and must be displaced by the pencil in entering the socket-piece, and in this way the tension of the limbs is utilized to hold the pencil in place in the socket-piece and is further utilized to firmly grasp the 50 edge of the pocket between the limbs and the pencil.

By the construction described, it will be seen that the limbs 2 and 3 constitute a hook for fastening the device and its attached pencil to the edge of a pocket and a pencil engaging spring combined. 55

What I claim is:—

1. A pencil clasp, having a socket-piece to receive the pencil, and a combined hook and pencil-engaging spring, said spring having a bar extending transversely across the socket to engage the pencil directly both when the 60 hook is and is not engaging the pocket.

2. A pencil clasp, having a socket-piece to receive the pencil, and a combined hook and pencil-engaging spring, said spring having a fixed limb and a free limb, the latter terminating in a bar projecting crosswise of the socket-piece, said bar adapted to engage the pencil directly both 65 when the hook is and is not engaging the pocket.

3. A pencil clasp, constructed of wire, and having a coil constituting the socket piece, a limb projecting from and rigid with the coil and returned as a free limb toward 70 the coil and having a terminal bar crossing the coil, said terminal bar adapted to constantly engage the pencil both when in and out of the pocket.

4. A pencil clasp, having a socket-piece to receive the pencil, and a combined hook and pencil-engaging spring, 75 said spring having a fixed limb and a free limb, the latter terminating in a bar projecting crosswise of the socket-piece, the free limb capable of adjustment to vary its effective tension.

In testimony whereof I have hereunto set my hand this 80 14th day of December A. D. 1906.

FREDERICK A. SCHNEIDER.
